DESIGN FOR A MULTIGEM SETTING OR SIMILAR ARTICLE

Samuel R. Donchi, South Orange, N. J.

Application January 15, 1948, Serial No. 143,808

Term of patent 14 years

(Cl. D45—1)

To all whom it may concern:

Be it known that I, Samuel R. Donchi, a citizen of the United States of America, residing in South Orange, county of Essex, and State of New Jersey, having a post-office address care of Schuman & Donchi, Inc., 155 Summit Street, Newark, New Jersey, have invented a new, original, and ornamental Design for a Multigem Setting or Similar Article, of which the following is a specification, reference being had to the accompanying drawing, forming a part thereof, in which:

Figure 1 is a top plan view of a multigem setting or similar article, embodying my new design;

Figure 2 is a side elevational view thereof; and

Figure 3 is an end view thereof.

I claim:

The ornamental design for a multigem setting or similar article, as shown.

SAMUEL R. DONCHI.
